UNITED STATES PATENT OFFICE.

MILTON L. DODGE, OF NEWBURYPORT, MASSACHUSETTS.

TURNED SHOE AND METHOD OF MAKING THE SAME.

1,221,153.

Specification of Letters Patent.

Patented Apr. 3, 1917.

Application filed August 22, 1916. Serial No. 116,331.

To all whom it may concern:

Be it known that I, MILTON L. DODGE, a citizen of the United States, residing at Newburyport, in the county of Essex and State of Massachusetts, have invented new and useful Improvements in Turned Shoes and Methods of Making the Same, of which the following is a specification.

The object of the present invention is to 10 provide a new and improved method of making "turned" shoes, and the invention relates particularly to the method of anchoring the forward extremities of a stiff molded counter-stiffener, whereby said extremities and the adjacent portions of the shoe upper will be caused to hug closely the arch portion of the foot.

A common method heretofore followed, in which a stiff molded counter-stiffener is used, 20 consists in nailing the heel-seat flange of such counter-stiffener to a flat nail-receiving member prior to assembling the counter-stiffener and such nail-receiving member with the other elements of the shoe. In 25 consequence of such former method the forward extremities of the counter-stiffener have been dependent for their anchorage upon the said nail-receiving member. Such nail-receiving members are usually made of relatively 30 cheap material such as fiber board and although the nails used to fasten the flange of the counter-stiffener to such nail-receiving member may have heads and may be turned back and clenched at their points, the 35 counter-stiffener does not have a sufficiently secure anchorage because the nail-receiving member is not sufficiently firm or tough to prevent the nails from working loose when the shoe is being worn. This is especially 40 true when the shoe has been wet, for when the fiber board or other cheap material of which the nail-receiving member is made becomes wet it loses substantially all its virtue as a means of anchorage for the nails. It 45 thus follows that the forward extremities of the counter-stiffener are forced apart, their anchoring nails become loose, if not fully freed from the nail-receiving member, and the shank portion of the shoe bulges, 50 destroying the fit of the shoe and causing an unsightly appearance.

According to my present invention the forward extremities of the stiff molded counter-stiffener are nailed directly to the sole of the shoe, and the nails used for such purpose being anchored in the sole, and preferably

clenched therein hold the extremities of the counter stiffener so firmly that such extremities can not become unfastened from their anchorage or caused to bulge, by the stresses 60 to which a shoe is ordinarily subjected while being worn. The term "nails" as used for the purpose of describing the present invention, is used in its broad sense to include tacks and staples. 65

Of the accompanying drawings,

Figure 1 represents a top plan view of a lasted shoe before being turned, and includes a stiff molded counter stiffener, the extremities of which are fastened to the sole of the 70 shoe by staples driven into the sole and clenched therein.

Fig. 2 represents a sectional view on a larger scale through the structure intersected by line 2-2 of Fig. 1, and includes a metal 75 nailing jack on which the shoe may be supported for driving the staples shown in Fig. 1.

Fig. 3 represents a vertical cross section through the structure intersected by line 80 3-3 of Fig. 1, and includes the nailing jack shown in Fig. 2.

Fig. 4 represents a vertical sectional view similar to Fig. 3, excepting that one of the staples has not been driven, and a steel plate 85 is arranged in the channel of the sole to turn back and clinch the points of the staple.

Fig. 5 represents a vertical section similar to Fig. 2 showing the shanks of the staple as having been driven all the way through the 90 sole and turned back and clenched by the nailing jack.

Fig. 6 represents a top plan view of the shoe after it has been turned and nailed around the heel portion. 95

Fig. 7 represents a sectional view through the structure intersected by the line 7-7 of Fig. 6.

Fig. 8 represents a sectional view similar to Fig. 7 excepting that the heel portion of the upper has not been connected to the sole. 100

The same reference characters indicate the same parts wherever they occur.

The lasting of a turned shoe may be completed before the shoe is turned, or the lasting of the heel end may be postponed until after the shoe has been turned. According to the method first stated it is common to continue the channel of the sole all the way around the latter, to perform the lasting substantially in one operation, and to connect the pulled-over portion of the upper with 105 110

the sole all the way around the shoe by sewing, prior to turning the shoe.

According to the second method the fore part and shank portion of the shoe would be pulled over and lasted and the pulled-over portion of the upper would be connected to the sole by stitching, leaving the heel portion of the shoe unlasted, and the heel portion of the upper disconnected, temporarily, from the sole. In this case the heel portion of the upper is pulled over, lasted, and nailed to the sole after the shoe has been turned.

I have described both the foregoing methods of lasting in order to indicate that my new and improved method of anchoring a stiff molded counter-stiffener to the sole may be followed in conjunction with either of the said methods of lasting.

Figs. 1 and 2 illustrate a shoe that has been lasted according to the method first described, that is, lasting is completed before the shoe is turned. The sole, upper, and lining of the shoe are indicated respectively at 10, 11, and 12. The lining is slit transversely at opposite sides of the shank portion as indicated at 13, 13, and that portion of the lining that is in front of the slits is lasted and sewn by the stitches 14 that contact the upper with the sole. The stitch-receiving channel of the sole is indicated at 15 and the channel-flap is indicated at 16. The rear portion 12' of the lining is not caught by the stitches 14 or otherwise fastened to the between substance, but is left free so that it may be tucked inside the counter-stiffener after the shoe has been turned.

Assuming that the shoe has been lasted and sewed according to the method first described, it is ready to receive a stiff molded counter-stiffener, but before the latter is attached the last should be removed from the shoe in order to permit the shank portion of the sole 10 to be straightened. I therefore remove the last from the shoe and place the shoe upon a suitable nailing jack such as that indicated at 17, the top surface of such jack being substantially flat for the purpose of sustaining the heel portion and shank portion of a sole in flat condition while the extremities of the counter-stiffener are being fastened. A stiff molded counter-stiffener is indicated at 18 and the heel-seat flange thereof is indicated at 19. This counter-stiffener is placed right side up on the sole 10 or on the marginal portion of the upper after the latter has been trimmed. Suitable fasteners are then driven through the forward extremities of the flange 19 and into the sole 10. For this purpose I have found staples desirable, and such staples are indicated at 20, 20. The extremities of the counter-stiffener are arranged so close to each other that they will cause the shank,

portion of the shoe to hug the shank portion of the foot.

The points of the staples may be turned back and clenched in the channel 15 or they may be driven all the way through the sole 70 and clenched against the nailing jack 17, but I prefer to clamp them in the channel because in that case they will not mar the appearance of the bottom of the sole when the shoe is finished. I will describe first 75 the method of clamping the points in the channel. Fig. 4 shows a staple that has not been driven but is in position to be driven. The element indicated at 21 is a thin steel plate. This plate serves as an anvil and its 80 function is to turn back and clamp the points of the staples in the channel. One marginal portion of the plate may be inserted into the channel as shown prior to driving the fastener. Thus when the shanks of 85 the staple have passed through the flange of the counter-stiffener and through the channel-flap 16 of the sole they will encounter the anvil 21 and be turned back and clenched substantially as shown by Fig. 2. 90 When one extremity of the counter-stiffener has been anchored in this manner the anvil 21 may be removed and then inserted into the channel in the opposite marginal portion of the sole. 95

If it is desired to drive the fasteners all the way through the sole, longer shanks would be necessary to cause the points to be turned back and clenched. However, a staple having shanks like those shown in Figs. 2, 3, and 4 would pass substantially all 100 the way through the sole, provided the anvil 21 were not used, but would not be long enough to be turned back and clenched by the nailing jack. It is to be understood that the fundamental principle of my improved method does not depend upon clamping the points of the fasteners. The feature that I consider broadly new is fastening the extremities of the counter-stiffener directly to the sole by fasteners extending through the flange and into the sole. However, if it is desired to drive the staples entirely through the sole and to turn back and clamp their points as shown by Fig. 5, the nailing jack 110 will promote such operation without the use of any additional anvil. 115

When the extremities of the counter-stiffener have been securely anchored to the sole by any one of the methods described, the shoe is ready to be turned. In the course of turning the shoe the loose rear portion 12' of the lining will be carried over the upper edge of the counter-stiffener so that it may be tucked inside the latter and cemented to the inner face thereof as shown by Figs. 7 and 8. Having turned the shoe and cemented the lining to the inner face of the counter-stiffener the next operation would be to insert a nail-receiving member 22 in 120 125 130

the heel portion and shank portion. The principal function of the member 22 is to afford anchorage for the usual heel-seat nails 23. The shoe shown by Fig. 7 is completely lasted before being turned, the upper and sole being connected by the stitches 14 around the heel portion as well as around the other portions. When my method of attaching a counter stiffener is practised in a shoe of this kind the anchoring of the counter-stiffener is completed by driving the heel-seat nails 23. When such heel-seat nails are driven they pass through the sole, through the pulled-over portion of the upper, through the flange of the counter-stiffener, through the corresponding flange of the lining and through the marginal portion of the nail-receiving member 22. The last, indicated at 24, is placed back in the shoe prior to driving the heel seat nails, and, being provided with a metal heel plate 25, points of the heel seat nails are turned back and clenched in the member 22 by the plate 25.

If the shoe is made according to the method that consists in leaving the heel portion in an unlasted condition until after the shoe is turned, the heel portion of the sole would be bent up as shown by Fig. 3 to enable lasting tacks 26 to be driven through the pulled-over portion of the upper, through the heel-seat flange of the counter-stiffener, through the corresponding marginal portion of the lining, and through the nail-receiving member 22. Such lasting tacks would be turned back and clenched in the member 22 by the metal plate 25 of the last. The anchoring of the counter-stiffener is thus substantially completed by driving the lasting tacks around the heel portion of the shoe, but after the heel portion has been thus lasted the heel portion of the sole must be laid down and anchored by heel-seat nails such as those indicated at 23 in Figs. 6 and 7. These heel-seat nails will also pass through the flange of the counter-stiffener and will be turned back and clenched in the nail-receiving member 22, so that the anchoring of the counter-stiffener around the heel portion will be doubly secure.

As my improved method of anchoring the counter-stiffener does not affect the remainder of the shoemaking operation, it will not be necessary to proceed further with a description of the latter.

I am aware that it is not new to drive fasteners through the heel-seat flange of a stiff molded counter-stiffener and through a nail-receiving member such as that indicated at 22, but so far as I am aware it is new to fasten the counter-stiffener to the sole prior to putting in the member 22, and it is also new to anchor the extremities of the counter-stiffener directly to the sole instead of to the member 22. The latter feature is the one

that enables the extremities of the counter-stiffener to be so firmly fastened in place that they can not be displaced laterally with relation to the sole and prevent the upper from bulging at the shank portion.

Although I have not shown or described any other means than metallic fasteners for anchoring the extremities of the counter-stiffener to the sole, the invention contemplates any kind of fasteners that would serve the purpose, and the term "fasteners" as used in the claims is intended to include stitches excepting where metallic fasteners are specifically recited.

I claim:

1. In the art of making "turn" shoes, the method comprising the steps of lasting the shoe and sewing the pulled-over portion of the upper to the sole, arranging a stiff molded counter-stiffener right side up on the heel portion of the shoe, anchoring the extremities of the counter-stiffener to the sole by driving fasteners through the flange of the counter stiffener and into the shank portion of the sole, turning the shoe, and anchoring the rear portion of the counter stiffener by driving metallic fasteners through the sole, around the margin of the heel-seat, and through said flange, and turning back and clenching the points of latter said fasteners.

2. In the art of making "turn" shoes, the method comprising the steps of lasting the shoe and sewing the pulled-over portion of the upper to the sole, arranging a stiff molded counter-stiffener right side up on the heel portion of the shoe, anchoring the extremities of the counter-stiffener to the sole by driving fasteners through the flange of the counter-stiffener and into the shank portion of the shoe, turning the sole, inserting a nail-receiving member in the heel portion of the shoe, and anchoring the rear portion of the counter-stiffener by driving metallic fasteners through the flange of the latter and through said nail-receiving member, and turning back and clenching the points of the latter said fasteners.

3. In the art of making "turn" shoes, the method comprising the steps of lasting the shoe and sewing the pulled-over portion of the upper to the sole, arranging a stiff molded counter-stiffener right side up on the heel portion of the shoe, anchoring the extremities of the counter-stiffener to the sole by driving nails through the flange of the counter-stiffener and into the sole, turning back and clenching the points of said nails, turning the shoe, and anchoring the rear portion of the counter stiffener by driving nails through the sole, around the margin of the heel-seat, and through said flange, and turning back and clenching the points of the latter said rails.

4. In the art of making "turn" shoes, the method comprising the steps of lasting the

shoe and sewing the pulled-over portion of the upper to the sole, arranging a stiff molded counter-stiffener right side up on the heel portion of the shoe, anchoring the 5 extremities of the counter-stiffener to the sole by driving nails through the flange of the counter-stiffener and into the sole, turning back and clenching the points of said nails in an incision in the sole, turning the 10 shoe, and anchoring the rear portion of the counter-stiffener by driving nails through the sole, around the margin of the heel-seat, and through said flange, and turning back and clenching the points of the latter said 15 nails.

5. In the art of making "turn" shoes, the method comprising the steps of lasting the shoe and sewing the pulled-over portion of the upper to a sole that has a stitch-receiving 20 channel, arranging a stiff molded counter-stiffener right side up on the heel portion of the shoe, anchoring the extremities of the counter-stiffener to the sole by driving nails through the flange of the counter-stiffener 25 and through the channel-flap of the sole, turning back and clenching the points of said nails in the stitch-receiving channel of the sole, turning the shoe, and anchoring the rear portion of the counter-stiffener by driving 30 nails through the sole, around the margin of the heel-seat, and through said flange, and turning back and clenching the points of the latter said nails.

6. In the art of making "turn" shoes, the 35 method comprising the steps of lasting the shoe and sewing the pulled-over portion of the upper to the sole, arranging a stiff molded counter-stiffener right side up on the heel portion of the shoe, anchoring the 40 extremities of the counter-stiffener to the sole by driving nails through the flange of the counter-stiffener, into the sole, and against an anvil arranged in an incision in the sole, to turn back and clench the points 45 of said nails between the inner and outer faces of the sole, turning the shoe, and anchoring the rear portion of the counter-stiffener by driving nails through the sole, around the margin of the heel-seat, and 50 through said flange.

7. A "turn" shoe comprising a sole, an upper, a counter-stiffener having a heel-seat flange, nails extending through the extremities of said flange and into the shank por-

tion of the sole, the heads of said nails being 55 seated against said flange and the points being clenched and arranged to coact with the sole, and nails extending through the heel-seat margin of the sole and through said flange, the latter said nails having heads 60 and clenched points.

8. A "turn" shoe comprising a sole, an upper, a counter-stiffener having a heel-seat flange, nails extending through the extremities of said flange and into the shank portion of the sole, the points of said nails being 65 clenched and arranged between the inner and outer faces of the sole, and nails extending through the heel-seat margin of the sole and through said flange, the latter said nails having heads 70 and clenched points.

9. A "turn" shoe comprising an upper, a sole having a stitch-receiving channel and a channel-flap, stitches connecting the upper and sole, said stitches being arranged in said 75 channel, a counter-stiffener having a heel-seat flange, nails extending through the extremities of said flange and through said channel-flap, said nails having clenched points arranged in said channel and having 80 heads, and nails extending through the heel-seat margin of the sole and through said flange, the latter said nails having heads and clenched points.

10. A "turn" shoe comprising an upper, a sole having a stitch-receiving channel and a channel flap, stitches connecting the upper and sole, said stitches being arranged in said channel, a counter-stiffener having a heel-seat flange, fasteners extending through 85 the extremities of said flange and through said channel flap, said fasteners being anchored to said flap in said channel, and fasteners extending through the heel-seat margin of the sole and through said flange. 90

11. In the art of making "turn" shoes, the method comprising lasting and uniting the upper and sole, and fastening a previously molded counter-stiffener directly to the sole by driving metallic fasteners through the forward extremities of the heel-seat flange of such counter-stiffener, and into the sole, whereby said extremities are held against displacement relatively to the sole. 95

In testimony whereof I have affixed my 10 signature.

MILTON L. DODGE.
